CLAIM

The ornamental design for pressed cannabis as shown and described herein.

DESCRIPTION

FIG. 1 is a top perspective view of pressed cannabis, showing our new design.

FIG. 2 is a top view thereof.

FIG. 3 is a bottom view thereof.

FIG. 4 is a front view thereof.

FIG. 5 is a back view thereof.

FIG. 6 is a left side view thereof.

FIG. 7 is a right-side view thereof; and,

FIG. 8 is a front exploded view of the pressed cannabis, shown in an environment of use.
The broken lines in the drawings are for the purpose of illustrating environmental structure and form no part of the claimed design.

1 Claim, 5 Drawing Sheets
